DESIGN FOR A LIPSTICK CONTAINER OR THE LIKE

Lucien Renaud, St. Albans, N. Y., assignor to Roger & Gallet, New York, N. Y., a corporation of New York

Application May 21, 1945, Serial No. 119,639

Term of patent 14 years

(Cl. D86—10)

To all whom it may concern:

Be it known that I, Lucien Renaud, a citizen of the United States and residing at 118-07 222nd Street, St. Albans, New York city, New York, have invented a new, original, and ornamental Design for Lipstick Container or the like, of which the following is a specification, reference being had to the accompanying drawing, forming part thereof.

Fig. 1 is a top plan view of a lipstick container or the like in closed position, showing my new design;

Fig. 2 is a side view slightly in perspective thereof;

Fig. 3 is a bottom plan view thereof; and

Fig. 4 is a side view thereof slightly in perspective with the cap removed.

I claim:

The ornamental design for a lipstick container or the like, substantially as shown.

LUCIEN RENAUD.
